Primary Examiner — Vy Koenig*Assistant Examiner* — Kimberly Barnes(74) *Attorney, Agent, or Firm* — Zuber Lawler & Del Duca LLP; Matthew J. Spark(57) **CLAIM**

The ornamental design for an architectural fixture, as shown and described.

DESCRIPTION

FIG. 1 is a perspective view of our new design for an architectural fixture;

FIG. 2 is a front elevational view thereof;

FIG. 3 is a right elevational view thereof;

FIG. 4 is a rear elevational view thereof;

FIG. 5 is a left elevational view thereof;

FIG. 6 is a bottom plan view thereof, and,

FIG. 7 is a top plan view thereof.

The broken lines in the accompanying figures depict portions of the architectural fixture that form no part of the claimed design.
